UNITED STATES PATENT OFFICE

ALMA L. ABBOTT, OF OMAHA, NEBRASKA

DESIGN FOR A BRUSH

Application filed February 20, 1931. Serial No. 38,743. Term of patent 3½ years.

To all whom it may concern:

Be it known that I, ALMA L. ABBOTT, a citizen of the United States of America, and a resident of Omaha, in the county of Douglas and State of Nebraska, have invented a new, original, and ornamental Design for Brushes, of which the following is a specification, reference being had to the accompanying drawing, forming part thereof.

I claim:

The ornamental design for a brush as shown.

In testimony whereof, I have affixed my signature.

ALMA L. ABBOTT.
